UNITED STATES PATENT OFFICE.

JAMES D. BENBOW, OF AURORA, ILLINOIS, ASSIGNOR TO WESTERN WHEELED SCRAPER COMPANY, OF AURORA, ILLINOIS, A CORPORATION OF ILLINOIS.

SCARIFYING MACHINE

Application filed September 19, 1921. Serial No. 501,730.

To all whom it may concern:

Be it known that I, JAMES D. BENBOW, a citizen of the United States, and a resident of Aurora, in the county of Kane and State of Illinois, have invented certain new and useful Improvements in Scarifying Machines, of which the following is a specification, reference being had to the accompanying drawings.

My invention relates to road making machinery, and has particularly to do with machines for scarifying or cutting up the road surface. It has for its object to provide improved means for lifting the frame which carries the scarifying teeth so that when raised such frame will be maintained in a substantially horizontal position, and also to provide means by which the operation of lifting the scarifier frame will be made easier. I accomplish my object as illustrated in the drawings and as herein-after described. What I regard as new is set forth in the claims.

In the accompanying drawings,—

Fig. 1 is a side elevation of a scarifying machine embodying my improvements, some parts being broken away;

Fig. 2 is a partial longitudinal sectional view on line 2—2 of Fig. 3;

Fig. 3 is a plan view of the scarifier frame, and the draft attachments therefor, some parts being in section, the view being taken substantially along the line 3—3 of Fig. 1;

Fig. 4 is a cross section on line 4—4 of Fig. 1; and

Fig. 5 is a partial cross section on line 5—5 of Fig. 1.

Referring to the drawings,—6 indicates

the main frame of the machine as a whole,

scarifier frame is provided with two rigid draft bars 13 and 14, the rear end portions of which are fixedly secured thereto at opposite end portions of said frame. Said draft bars extend forward and converge, 60 their forward ends being connected by a cross plate 15, thus forming a rigid V-shaped draft frame. This draft frame is connected with the usual king bolt 16 which is fitted in the front axle frame 9, by means 65 of draft bars 17, 18 which are connected together at their forward end portions to form a goose neck 19 which is pivoted upon the king bolt 16, as shown in Figs. 1 and 3. The rear portions of said draft bars overlap the forward end portions of the bars 13, 14, and are pivotally connected therewith by pivots 20, 21 so that the draft frame comprising the bars 13, 14 can swing vertically about said pivots. This draft frame extends forward 70 some considerable distance beyond the pivots 20, 21, and the forward end of said frame is connected to the lower end of a spring 22, the upper end of which is secured to an inverted V-shaped frame 23 fixedly mounted 75 upon and rising from the forward portion of the main frame 6. This spring tends to lift the forward end of the scarifier draft frame, but inasmuch as the scarifier teeth 12 are located back of the pivots 20, 21, when 80 the machine is in use the resistance due to the engagement of such teeth with the ground tends to swing the forward end of the scarifier frame down, to its operative position, where it is locked by a latch hereinafter described. For preventing downward movement of the forward end of the scarifier frame beyond its proper operative 85 position, the draft bars 17, 18 are provided with a web 24 which underlies the forward 90

end of the bars 13, 14, and is secured to the frame 6. The web 24 is provided with a slot 25 which receives the forward end of the draft bars 13, 14, so that the web 24 will 95 prevent the forward end of the draft frame from being lowered below the level of the main frame 6. The web 24 is provided with a slot 25 which receives the forward end of the draft bars 13, 14, so that the web 24 will 95 prevent the forward end of the draft frame from being lowered below the level of the main frame 6.
